UNITED STATES PATENT OFFICE.

JAMES A. LEONARD, OF LEWISTON, MAINE, ASSIGNOR TO S. MORGAN SMITH COMPANY, OF YORK, PENNSYLVANIA, A CORPORATION OF PENNSYLVANIA.

COMBINATION TRASH RACK AND RADIAL GATE.

Application filed March 23, 1925. Serial No. 17,728.

This invention relates to trash racks for water power plants, and the purpose of the same is to prevent floating or water-logged timber, ice, branches of trees and other débris from clogging the passages of water wheels or runners of turbine and other analogous installations.

These racks usually consist of metal bars arranged in the form of a grating and spaced in accordance with the dimensions of the wheel or runner, the said racks being disposed a short distance upstream from the entrance to the wheel chambers or flumes, so that any water reaching the turbines must first pass through the racks, and by this means all débris is caught and held and prevented from reaching the water wheels. A common practice has been to fix these racks firmly in position, and the trash can only be removed by the efforts of one or a number of operators laboriously raking them with long-handled rakes or by means of expensive and complicated machines of doubtful value.

The present invention consists in fastening a rack of suitable design to a properly formed radial or "Taintor" gate, the rack and gate being so arranged that when the gate is lifted through the water to a predetermined elevation or proper position, the rubbish or débris which has collected on the rack will be washed automatically from the surface of the rack and carried downstream over a properly designed spillway or through a trough or canal.

The advantages of the proposed improvements are manifold and among others may be mentioned that owing to the combination of the head gate and rack, the initial expense of construction and installation is considerably less than by the use of the older fixed form of rack, and considerable saving ensues in the construction of the masonry of the intakes. With a motor operated hoist of well understood form one operator can clean all of the racks in a large power plant in a short time. As each water wheel or turbine is provided with two or more gates and racks, the racks can be thoroughly cleaned without shutting down the wheel, and furthermore, in case of damage to the racks, they can be lifted entirely out of the water and the full length thereof will then be exposed to view for inspection

and repair. Owing to the fact that the racks and gates are entirely submerged below the ice line, neither fixed ice nor so-called "anchor ice" will interfere with them, and the submergence of the bars constituting the components of the rack in water below the frost line will prevent ice from freezing to them, and as a consequence the ordinary trouble resulting from "anchor ice" will be largely eliminated. It is also possible in accordance with the features of the present invention and desirable that under certain conditions the gates be made entirely automatic by means of motors operated by a float located back of or downstream from the racks, and by this means, when the racks become so clogged with leaves, ice or other débris that the surface of the water is lower back of the racks than upstream, the float will start the motor and the racks will rise until the débris is washed off; after which the water will assume the same elevation above and below the rack and gate, and the rack will then be automatically lowered to its first or normal position.

In the drawings preferred embodiments of the improved trash rack and gate are shown to illustrate the essential features of the invention, and therein:—

Fig. 1 is a cross section through a turbine installation and the masonry incident thereto together with the intake therefor, showing the improved combined rack and gate in transverse section in closed and open positions, respectively, in full and dotted lines together with means diagrammatically illustrated for controlling the open and closed positions of the combined device.

Fig. 2 is an elevation of a portion of the bottom or arcuate or gate member of the improved rack and gate.

Fig. 3 is a transverse vertical section on an enlarged scale of the improved rack and gate.

Fig. 4 is a front side elevation of a portion of the rack, showing the rods or bars and the means for holding the same.

Fig. 5 is an enlarged transverse vertical section showing means for forming a water seal at the horizontal sill at the bottom of the gate.

The numeral 5 designates masonry or concrete work comprising a chamber or passage

6 in which is installed a turbine 7, an intake 8 and a tail-race 9, into which the draft tube 10 of the turbine discharges in a well known manner. The turbine as shown by Fig. 1 is 5 of the horizontal type but may be replaced by the vertical type of turbine. The intake 8, as usual, is located at the upstream portion of a flume or raceway 11, and above the same and the turbine installation and masonry 10 is a motor hoist 12, which is diagrammatically represented, having a cable or analogous device 13 associated therewith and depending therefrom for a purpose which will be presently explained. A spillway 14 is provided over the arch or enclosure 15 of masonry or concrete work for forming the passage or chamber 6, and at the base of the intake is an elevated breast or ridge 16 of masonry or concrete work, 15 preferably of truncated form, to provide a bottom sill which forms part of a gate and trash-rack-receiving space or seat 17, located immediately in rear thereof. All of the features of structure thus far described are 20 well known in the art of turbine installation and may be modified indefinitely, as the features of the invention are not dependent upon any precise structure of masonry or concrete work and particular turbine installation and spillway or analogous relief means. 25

The essential feature of the invention consists of a combined trash rack 18 and gate 19, presenting a substantially triangular structure which is pivoted at its apex or upper end 20 to any suitable supporting means for a pivot or fulcrum 21, which is preferably located at the upper forward extremity of the arch or enclosure 15. The 30 combined trash rack and gate as shown by Figs. 1 and 3 has an arcuate base or bottom 22, constituting the gate member, the curve of this member being struck from the upper pivot 21 as a center. The combined trash rack and gate which is shown on an enlarged scale by Fig. 3 may be constructed in any manner desired to obtain economy in organization and at the same time give the greatest efficiency and strength and durability in service. Generally speaking, the 35 rack and gate will respectively comprise a number of I-beams 23 and 24 associated to diverge towards the bottom or gate member 22 from the upper reduced extremity of the device and counter-braced, for instance, by I-beams 25 connecting the beams 23 of the trash-rack member 18. At the upper converged end of the gate a suitable beam-embracing structure or web 26 will be applied, and at the lower end of the trash rack reinforcing beams 27 and braces 28 will be 40 provided as shown by Fig. 3. Between the lower or divergent ends of the beams 23 and 24 the arcuate bottom or gate member 22 of the combined device is located and con-

sists preferably of a suitable sheet metal closure 29 with cross beams 30 of I-form, which are secured at their ends to the end structures of the combined rack and gate. At intervals, also, tie braces or reinforcing devices 31 will be introduced between the beams 23 and 24 at a comparatively short distance upwardly from the arcuate gate 22 comprising the metal sheathing 29, and as may be found necessary in various installations to meet different contingencies other structural features may be added to increase the operative efficiency of the combined rack and gate, the essential feature of which is the combination of the two devices. Over the beams which are spaced at regular intervals, bars or rods 32 are secured and spaced any suitable distance and also braced between the beams 23 by rods 33. The rods or bars 32 may be of any form and extend fully across the rack. The rear beams 24 are spaced apart a suitable distance to provide for free passage of water into the chamber 6 for supplying the turbine installation and materially adding to the strength of the complete device. The cable, chain or analogous device 13 depends from and is attached to the lower reinforced construction of the rack 18 as indicated in full and dotted lines in Fig. 1, so that the motor-operated hoist 12 may raise and lower the combined rack and gate as also indicated by full and dotted lines in Fig. 1.

A special form of water seal organization is provided for the bottom of the combined rack and gate and particularly for cooperation with the arcuate sheet metal enclosure 29 comprised in the structure of the arcuate base or bottom 22 which constitutes the gate member. This water seal organization is illustrated on an enlarged scale by Fig. 5 and is located at the upper reduced portion of the breast or ridge 16 which provides the bottom sill for the gate. This water seal organization comprises in its preferred construction a cast-iron or other metallic box 34 having a perforated removable cover or closure 35, the box with its cover being inset in the upper rear angle of the sill. The box or enclosure 34 has a rear inclined side 36 with an opening 37 extending the full length thereof, and in this box or enclosure a steel or other suitable rod 38 is loosely mounted and has a rubber or analogous sheathing or covering 39. The bottom of the box or enclosure as at 40 is inclined downwardly and rearwardly to assist in the operation of the rod 38. When the arcuate gate or member 22 is raised to shut the water out of the flume, the rod 38 will roll against the gate and the pressure of the water admitted through the perforations or apertures of the lid or cover will force the rod tightly against the gate, in view of the fact that a portion of the said

rod will be projected through the opening 37. As there is no water pressure back of the gate or the rod, the desired tight seal between the rod and the arcuate gate will 5 be maintained and prevent leakage of the water between the gate and the sill. By this means, when the gate is raised to bring the rack member 18 into upper position for 10 cleaning purposes, the water will be completely shut off from the turbine.

The operation of the improved combined rack and gate structure is very simple. When the combined device is elevated as illustrated by dotted lines through the operation 15 of the chain, cable or analogous device 13, the rack 18 is disposed at the upper level of the water, which flows over the rack and washes off the collected débris therefrom, the débris passing rearwardly through the spill- 20 way or other outlet 14 downstream and away from the installation. After the rack has been cleaned, it will be lowered to the position shown in full lines by Fig. 1 through a reverse operation of the cable, chain or 25 similar device 13, thereby bringing the rack 18 into normal position and opening the flume for the free flow of water to the turbine installation.

Instead of using the motor hoist 12 with 30 its cable or analogous device 13 as shown, any suitable means may be adopted which performs the same function and including the well known float organization. It is also proposed to modify the proportions of the 35 several parts of the combined device to adapt the same to various applications, and further, to incorporate therein various structural features that will add to the strength and durability of the complete combined 40 rack and gate. It will be obvious that the combined rack and gate herein disclosed may operate with either a horizontal or vertical turbine installation with equal efficiency.

What is claimed as new is:

45 1. In a device for water power plants of the class specified, the combination with a part of the plant, of a radial gate converging towards its upper extremity and pivotally attached to a part of the plant at said extremity, the gate comprising a front straight rack and a lower curved closed bottom uniformly movable with the said straight rack.

50 2. In a device for water power plants of the class specified, the combination with a portion of the plant, of a radial gate comprising a front straight rack and a lower curved closed bottom connected for uniform movement and converging towards the upper reduced extremity of the gate which is pivoted to a part of the plant and whereby the front rack may be elevated for cleaning the same and the flow of water shut off by the bottom part of the gate.

55 3. In a water power plant, the combina-

tion with a flume, an upper overflow means and a turbine installation, of a radial gate converging towards its upper extremity and having said extremity pivotally connected to a part of the plant below the overflow, the 70 gate comprising a front straight rack and a lower curved closure connected to and movable uniformly with the rack whereby the rack may be raised for cleaning and the flow of water to the turbine installation checked 75 during the cleaning operation.

4. The combination of a water power plant comprising a flume, an upper overflow from the flume and a turbine installation around which the overflow passes, a radial 80 gate converging towards its upper extremity and pivoted to a part of the plant below the overflow and comprising a forward straight rack and a lower closed curved gate connected to the rack for unitary movement, the 85 combined rack and gate having a substantially triangular form and whereby when the rack is raised for cleaning purposes the gate will cut off the flow of water from the flume.

5. The combination of a water power 90 plant comprising a flume, a turbine installation and an upper overflow around the turbine installation, a combined forward rack and lower arcuate closing gate connected to the rack for unitary movement therewith, 95 the rack and gate having a substantially triangular form and pivotally connected to a part of the plant at its upper reduced apex extremity, and means connected to the lower portion of the rack for raising the latter 100 within the cleaning influence of the overflow means and bring the arcuate gate in closing position relatively to the flume and, conversely, for lowering the rack and the arcuate gate. 105

6. A water power plant comprising a flume, a turbine installation, an upper overflow from the flume around and past the turbine installation, a lower seat structure at the base of the flume and in advance of the 110 turbine installation, and a forward rack having a lower arcuate closing gate connected thereto for unitary movement, the rack and gate being of substantially triangular form and pivotally connected at the upper reduced apex extremity thereof to a part of the plant, the lower arcuate gate normally resting in the said seat, and means for raising and lowering the unitary rack and gate. 115

7. A device for water power plants of the 120 class specified consisting of a rear frame, a front rack and a lower closure structure all connected to move as a unit, the frame and rack diverging from an upper reduced extremity to the said closure means, and means for pivotally mounting the upper reduced extremity of the device. 125

8. A turbine installation, a flume leading to the latter, and an overflow at the upper 130 part of the flume around the turbine instal-

lation, all of the class specified, and a lower gate and a front rack connected to and movable as a unit with the gate in the flume in advance of the turbine installation, the gate and rack having dimensions corresponding to the depth and width of the flume, the gate having a vertical extent when open to exclude the flow of water thereover or thereunder to the turbine installation.

9. The combination with a water power plant having a turbine installation and a supply flume with an intake communicating with the chamber of the said installation, of a lower gate and front rack connected for unitary opening and closing movements and disposed in the said intake, the unitary gate and rack being pivoted at the upper extremity thereof, the flume having relief means for carrying the water past the turbine installation, and means for raising and lowering the combined gate and rack, the rack and gate when elevated closing off the flow of water to the turbine installation and permitting the rack to be automatically cleaned by the water flowing thereover.

10. The combination with a turbine installation having a water supply communicating with a flume by means of an intake, the flume being provided with means for carrying the water downstream past the installation, a forward rack means and lower gate combined for unitary movement and pivotally connected at the upper extremity thereof to a part of the turbine installation, operating means connected to the rack and gate for raising and lowering the same, movable means located at the lower forward portion of the installation for forming a watertight joint with the gate, the rack being exposed when elevated to a cleaning flow of the water to remove trash, débris and other accumulations therefrom.

11. The combination with a turbine installation having water supply means, of a rack pivotally connected at its upper end to a part of the installation and provided with a lower arcuate closing gate movable as a unit therewith and of such extent as to prevent overflow of the water of the supply means thereover to the turbine installation, and mechanism for raising and lowering the rack and gate, the rack when raised being automatically cleaned and freed of trash, débris and other accumulations by the water flowing thereover and the liberated trash,

débris and other accumulations carried off clear of the turbine installation.

12. A turbine installation having a water supply means combined with a rack having a lower closing gate connected to and movable as a unit with the rack, the rack and gate unit being pivoted at its upper extremity to respectively elevate the rack to an upper portion of the supply means and vertically through the latter to permit the water to automatically clean the rack and cause trash, débris and other accumulations to flow away clear of the turbine installation and also during such latter operation to cause the gate to shut off the water supply from the turbine installation.

13. The combination with a turbine installation including masonry forming a supply chamber for the turbine and also providing an intake having a lower sill, of a rack pivotally connected at its upper end to the upper portion of the installation and having a gate secured to and movable therewith as a unit upwardly and downwardly through the supply means, the gate moving close to the rear portion of the sill, operating means for raising and lowering the rack and gate, and a water seal organization mounted in the sill and consisting of a movable means controlled by water pressure to contact with the gate and prevent leakage of water through the lower portion of the gate when the latter is raised to cut off the supply of water to the turbine installation and dispose the rack in position for cleaning accumulations therefrom.

14. The combination with a turbine installation including chambered masonry having water supply means and an intake together with a lower sill, of a rack pivotally connected at its upper end to a portion of the installation and having a lower gate of such dimensions as to shut off the supply of water relatively to the turbine when the rack and gate are elevated, automatically movable means mounted in the sill and engaging the gate to prevent leakage of water between the gate and means when the gate is being elevated, the elevation of the rack effecting an automatic cleaning of the same by the water from the supply means flowing thereover.

In testimony whereof I have hereunto set my hand.

JAMES A. LEONARD.
